DOOR MECHANISM

Conrad R. Vegren, Chicago, Ill., assignor to Camel Company, Chicago, Ill., a corporation of Illinois

Application March 17, 1933, Serial No. 661,254

10 Claims. (Cl. 16—99)

This invention relates to door mechanism and particularly to that type of mechanism by which a door for railway house cars may be elevated and supported for longitudinal movement toward 5 open and closed positions.

It is an object of this invention to provide mechanism for elevating and supporting longitudinally movable doors which shall involve a reduction in the number of parts heretofore required, a substantial decrease in the friction and wear between movable parts of said mechanism, elimination of error in application and accuracy of operation thereof.

A further object is to provide a mechanism for elevating and supporting longitudinally movable doors capable of imparting a closing movement to said doors during the lowering movement thereof and an opening movement thereto during the elevation thereof.

20 A further object is to provide mechanism for elevating and supporting longitudinally movable doors in which the moment of the door tending to resist elevation thereof will be substantially constant throughout the entire elevation of said doors.

Other objects will become clear as the description of the invention proceeds.

In the drawings forming part of this specification

30 Figure 1 is a partial elevation of a car door embodying the mechanism of the instant invention, the door being shown in lowered position;

Figure 2 is a view similar to Figure 1, showing the door in elevated position;

35 Figure 3 is an enlarged fragmentary elevation of the lower left hand corner of the door;

Figure 4 is a vertical section taken on line 4—4 of Figure 3;

Figure 5 is a horizontal section taken on line 40 4—5 of Figure 3;

Figure 6 is a horizontal section similar to Figure 5 through the lower right hand corner of the door;

Figure 7 is an enlarged fragmentary elevation 45 of the lower portion of the operating lever;

Figure 8 is a vertical section taken on line 8—8 of Figure 7;

Figure 9 is a side elevation of the roller retainer; and

50 Figure 10 is a section taken on line 10—10 of Figure 9.

Referring to the drawings in which a preferred embodiment of the invention is illustrated the numeral 10 designates a portion of the side wall 55 of a railway house car that embodies the door 11

on which the invention is shown. The track 12 extending outwardly beyond the side wall 10 is carried by the car by means of a plurality of track brackets 13 to which the track 12 may be secured as by rivets 14.

The door 11, as clearly shown in Figures 1, 2 and 3 of the drawings, which is adapted to be supported normally in frictional engagement with the track 12, is preferably of metallic construction and comprises a metallic panel 15 provided with a plurality of spaced horizontal corrugations 16, which, with the exception of the lowermost corrugation, merge at their ends into vertical corrugations 17 and 18 formed in said panel adjacent the vertical margins of the door. The margins of the door are usually reinforced by means of structural members secured thereto and, as clearly illustrated in Figure 4 of the drawings, the lower margin of the door is provided with an angle member 19 which serves to reinforce the lower margin of the door and to have frictional engagement with the track in the normal or lowered position of the door.

A roller 20 is disposed preferably adjacent each of the lower corners of the door in engagement with the track 12 and to permit such engagement between the roller and the track the angle bar 19 is coped as indicated at 21, illustrated in Figure 4 of the drawings. A roller retainer 22 is provided for each of said rollers which are retained in said retainers by means of the pins or axles 23 extending through the roller. Roller bearings 24 are preferably provided for said rollers. Each of the retainers 22 comprises preferably side walls 25 and 26 provided with the aligned openings 27 and 28 into which the pin 23 is adapted to extend in tight engagement therewith. The retainer is provided with a top wall 29 which, as shown in Figure 9 of the drawings is preferably arcuate and provided with a recess 30. A plurality of lugs 31 and 32 extend from the side wall 26 of the roller retainer adjacent the opening 28 formed therein. A projection 33 extends from said side wall 26 adjacent the arcuate wall 29 of the retainer.

Each of the retainers with its corresponding roller is adapted to be maintained in proper position relative to the door by means of a plurality of brackets 34 and 35 secured to said door preferably by means of rivets. Each of the brackets 34 and 35 is formed so as to provide attaching flanges 36 and an outwardly extending portion 37 in which the roller retainers are disposed. The outwardly extending portion 37 of each of the brackets embodies a substantially 50 55

horizontal outwardly extending flange 38 forming a trackway from which a tooth or lug 39 depends and which, in the normal or lowered position of the door, is received in the recess 30 provided in each of the roller retainers. The forwardly extending portion 37 of the brackets is formed so as to provide an arcuate slot 40 which receives the projection 33 of each of the roller retainers. Said forwardly extending portion 37 10 is provided with an additional arcuate slot 41 which in the bracket 34 opens outwardly as indicated at 42. The adjacent portions of the brackets 34 and 35 are curved as indicated at 43 and 44 so as to conform to the lower horizontal corrugation 16 provided in the door panel. The ends of said horizontal corrugations, as indicated at 45 and 46, are open so as to communicate with the brackets 34 and 35 and the retainers disposed therein whereby a bar 47 disposed 15 in said horizontal corrugation and provided with downturned end portions 48 and 49 may be connected by means of said end portions to the retainers in order to insure simultaneous operation thereof. The connection between said bar and the retainers may be obtained by means of lugs 50 and 51 which extend through openings provided in the ends of said bar. The mechanism contains an operating lever 52, the lower end of which is provided with an opening 53, through which the spaced lugs 31 and 32 of one 20 of the retainers is adapted to extend. The opening 53 is preferably reinforced by means of the wall 54 which lies between said lugs. The operating lever 52 is provided with a hand portion 55 and adjacent thereto with a rearwardly positioned spaced flange 56 adapted to lie behind a quadrant 57 secured to the door. A fixed handle 58 may be provided on the door as indicated in Figure 1 of the drawings.

In the assembly of the above described mechanism with the door the operating lever 52 may be inserted through the outwardly opening portion 42 of the arcuate slot 41 into the bracket 34. The roller and retainer assembly may then be inserted into the bracket through the rear thereof so that the lugs 31 and 32, provided on the retainer, extend into the opening 53 formed in the lower portion of the lever. The tooth 39 is positioned within the recess 30 of the retainer and the projection 33 disposed within the arcuate slot 40 formed in the outwardly extending portion 37 of the bracket. The bracket 35 may be assembled with its retainer and roller in the same manner. The connecting bar 47 may then be inserted into the lower horizontal corrugation 16 from the rear of the door and the ends thereof engaged with the lugs 50 and 51 provided on the roller retainers. The corrugation may then be covered by means of a backing plate 59 and the brackets and backing plate riveted to the door in order to complete the assembly. It will be observed from the foregoing that the retainers are disposed within their respective brackets independently of the door and said brackets.

When it is desired to move the door longitudinally of the car the handle 55 of the operating lever 52 is grasped and a downward pull exerted thereon in order to elevate the door above the track. When the end of the lever 52 is pulled downwardly engagement between the arcuate top wall 29 and the trackway provided by the flange 38 is obtained. The contour of the arcuate wall is so designed that during the downward movement of the lever said arcuate wall will roll on the

trackway, this rolling engagement being insured by means of the interengagement of the tooth 39 depending from the flange 38 and the recess 30 formed in the retainer. As the upper wall of the retainer rolls on the trackway an upward force is exerted upon the bracket so as to elevate the door, this force being imparted to both of the brackets because of the connection therebetween by means of the connecting bar 47. Each of the retainers will be guided in a plane substantially parallel to the door by the travel of the projections 33 within the arcuate slots 40. The maintenance of the retainers in this plane is further obtained by means of the extension of portions of the arcuate top wall of the retainers as indicated at 60 and 61, which provide increased bearing surface between the retainers and the trackways provided on the brackets and position the vertical edges of the retainers in proximate relationship to the outwardly extending wall of the brackets and the panel of the door. Each of these features, it will be apparent, tends to prevent any angularity between the roller retainers and the door. The movement of the retainers and the rollers therein in a plane substantially parallel to that of the door may be enhanced by the provision of a plurality of teeth depending from the trackway of each of the brackets and a plurality of corresponding recesses provided in the top walls of the retainers, and this construction is contemplated by the invention. It will be apparent, furthermore, that as the door is elevated through actuation of the operating lever 52, it will have imparted thereto a longitudinal movement in the direction of opening travel of the door. Similarly, in the lowering of the door which occurs automatically upon release of the lever 52, a longitudinal movement of the door in the closing travel thereof will be obtained. It is to be observed that the mechanism is so designed as to obtain a definite relationship between the center of swinging movement of the operating lever and the center of the arcuate top wall 29 of the retainers. In other words, as the operating lever is actuated to elevate the door it will swing about a center lying on the axis of the roller pin 23 but said center, as will clearly appear from an examination of Figures 1 and 2 of the drawings, has relative longitudinal movement with respect to the door. Thus, relative to the door the center of swinging movement of the lever shifts during the elevation of the door. Moreover, in the illustrated embodiment of the invention the arcuate wall 29 of each roller retainer has a compound curvature clearly evident from an examination of Figure 9 of the drawings. By means of this construction resulting in the above-noted relationship rolling engagement between the retainer and the trackway is obtained and this construction and relationship, moreover, in accordance with the disclosure of the drawings, insures that the perpendicular distance from the center of swing of the lever to the vertical plane extending at right angles to the door including the point of application of the weight of the door upon the retainer during the elevation of the door will be constant. For example in the movement of the door from the position shown in Figure 1 of the drawings to that shown in Figure 2 during which the rollers remain substantially stationary upon the track the points of contact between the arcuate wall of each of the retainers and the corresponding trackway will lie substantially in a vertical plane disposed at right angles to the door. As a result of this fact it will be

apparent that the moment of the door about the center of swing of the lever tending to resist elevation of the door as a result of the weight thereof, will be constant for all elevated positions 5 of the door. After the door has been elevated the weight thereof will be carried by the rollers and said door may then readily be moved longitudinally of the car as desired.

It is apparent that numerous changes and modifications in the details of the invention will be clear to those skilled in the art. It is intended, therefore, that all such changes and modifications be comprehended within this invention, which is to be limited only by the scope of the claims 15 appended hereto.

I claim:

1. In a railway house car, the combination with a longitudinally movable door and a track for frictionally supporting said door, of brackets secured to said door adjacent the lower corners thereof, said brackets having portions providing track means and arcuate slots, roller retainers disposed in said brackets having projections, rollers carried by said retainers in engagement with said door track, said retainers having arcuate portions adapted for rolling engagement on said track means, means for effecting rolling engagement between said retainers and said track means to elevate said door, said projections extending 30 into said slots to guide said retainers in a substantially vertical plane.

2. In a railway house car, the combination with a longitudinally movable door and a track for frictionally supporting said door, of brackets secured to said door adjacent the lower corners thereof, said brackets having portions providing track means, roller retainers independent of said door disposed in said brackets in substantially parallel relationship to said door, rollers carried 40 by said retainers in engagement with said door track, said retainers having arcuate portions adapted for rolling engagement on said track means, means for effecting rolling engagement between said retainers and said track means to elevate said door, parts of the arcuate portions of said retainers being widened to lie in proximate relationship to said door and said brackets to maintain the parallel relationship between said retainers and said door.

3. In a railway house car, the combination with a longitudinally movable door and a track for frictionally supporting said door, of brackets secured to said door adjacent the lower corners thereof, said brackets having portions providing track means, lugs depending from said track means, roller retainers disposed in said brackets, rollers carried by said retainers in engagement with said door track, said retainers having arcuate portions adapted for rolling engagement on said track means provided with recesses for receiving said lugs when said door is frictionally supported on said track and means for effecting rolling engagement between said retainers and said track means to elevate said door.

4. In a railway house car, the combination with a longitudinally movable door and a track for frictionally supporting said door, of brackets secured to said door adjacent the lower corners thereof, said brackets having portions providing track means, roller retainers disposed in said brackets, rollers carried by said retainers in engagement with said door track, said retainers having arcuate portions adapted for rolling engagement on said track means, means for effecting rolling engagement between said retainers

and said track means to elevate said door, said means comprising a lever extending through a slot in one of said brackets and secured to the retainer disposed therein.

5. In a railway house car, the combination with a longitudinally movable door and a track for frictionally supporting said door, of brackets secured to said door adjacent the lower corners thereof, said brackets having portions providing track means, roller retainers disposed in said brackets, rollers carried by said retainers in engagement with said door track, said retainers having arcuate portions adapted for rolling engagement on said track means, means for effecting rolling engagement between said retainers and said track means to elevate said door, said means comprising a lever secured to one of said retainers and capable of relative longitudinal movement with respect to said door and said bracket.

6. In a railway house car, the combination with a longitudinally movable door and a track for frictionally supporting said door, of brackets secured to said door adjacent the lower corners thereof, said brackets having horizontally disposed flanges providing track means, lugs depending from said track means, roller retainers disposed in said brackets, rollers carried by said retainers in engagement with said door track, said retainers having arcuate portions adapted for rolling engagement on said track means provided with recesses adapted for intermeshing relationship with said depending lugs and means for effecting rolling engagement between said retainers and said track means to elevate said door.

7. In a railway house car, the combination, with a longitudinally movable door and a track for frictionally supporting said door, of brackets secured to said door adjacent the lower corners thereof, said brackets having horizontally disposed flanges providing track means, roller retainers associated with said brackets, rollers carried by said retainers in engagement with said door track, said retainers having arcuate portions adapted for rolling engagement with said track means for elevating said door and means including an operating lever for actuating said retainers to effect rolling engagement between the arcuate portions of said retainers and said track means to elevate said door.

8. In a railway house car, the combination with a track and a door movable longitudinally upon said track, said door being frictionally supported upon said track in lowered position, of a member secured to said door adjacent each vertical edge thereof, a roller retainer associated for rolling engagement with each of said members, a roller mounted in each retainer in engagement with said track and means for imparting movement of rotation to said retainers about said rollers as fulcrums to effect rolling engagement between said retainers and said members whereby to elevate said door above said track and support the weight thereof upon said rollers.

9. In a railway house car, the combination with a track and a door movable longitudinally upon said track, said door being frictionally supported upon said track in lowered position, of a member secured to said door adjacent each vertical edge thereof, and a roller retainer having an arcuate portion associated for rolling engagement with each of said members, a roller mounted in each retainer in engagement with said track and means for imparting movement of rotation to said retainers about said rollers as fulcrums.

to effect rolling engagement between said arcuate portions and said members whereby to elevate said door above said track and support the weight thereof upon said rollers.

5 10. In a railway house car, the combination with a track and a door movable longitudinally upon said track, said door being frictionally supported upon said track in lowered position, of brackets secured to said door adjacent the vertical edges thereof, roller retainers having arcuate

portions associated for rolling engagement with said brackets, rollers mounted in said retainers in engagement with said track means for effecting rolling engagement between the arcuate portions of said retainers and said brackets to elevate said door above said track for movement upon said rollers, said retainers coacting with said brackets to impart opening movement to said door during the elevation thereof.

5 CONRAD R. VEGREN. 10
